[57] ABSTRACT

A discharge display device is disclosed which has upper and lower plates at least one of which is made transparent, a spacer disposed between said upper and lower plates, at least one cathode and at least one anode disposed between said spacer and said upper plate in opposed relation to said cathode, an adhesive agent sealing said upper and lower plates in an airtight manner along their outer edges to form an envelope and an inert gas sealed within said envelope. In this case, at least said spacer is covered with an insulating porous layer.

DISCHARGE DISPLAY DEVICE BACKGROUND OF THE INVENTION

1

1. Field of the Invention

This invention relates generally to a discharge display device, and more particularly to a discharge display device employing a novel spacer.

2. Description of the Prior Art

In the prior art, discharge display device in which the response time interval is short and a discharge between a pair of the cathode and anode is rapidly transferred to another pair of the cathode and anode of the discharge display device are not known.

Accordingly, the prior art discharge display device can not be used in place of a Braun tube.

SUMMARY OF THE INVENTION

According to an aspect of this invention there is proposed a discharge display device which consists of upper and lower plates at least one of which is made transparent, a spacer disposed between said upper and lower plates, a plurality of cathodes disposed side by side between said spacer and said lower plate and selectively supplied with a voltage, a plurality of anodes disposed side by side between said spacer and said upper plate in opposed relation to said spacer and said cathodes, an adhesive agent sealing said upper and lower plates in air-tight manner along their outer edges, and an inert gas sealed within said upper and lower plates, at least said spacer being covered with an insulating porous layer.

Accordingly, it is an object of this invention to provide a novel discharge display device.

It is another object of the invention to provide a discharge display device which has a short response time.

It is a further object of the invention to provide a discharge display device in which a discharge between a pair of the cathode and anode can be rapidly transferred to another pair of cathodes and anodes.

It is a yet further object of the invention to provide a discharge display device employing a novel spacer.

It is a still further object of the invention to provide a discharge display device which can be used in place of a Braun tube.

The other objects, features and advantages of the invention will become apparent from the following description taken in conjunction with the accompanying drawings.

BRIEF DESCRIPTION OF THE DRAWINGS

FIG. 1A is a fragmentary perspective view, partly in cross-section, showing one example of the discharge display device according to this invention;

FIG. 1B is an exploded perspective view, partly cut away, showing the principal part of the example depicted in FIG. 1A;

FIG. 2A is a fragmentary cross sectional view of a spacer employed in the example shown in FIG. 1A;

FIG. 2B is a schematic circuit diagram employed in experiments of spacer materials;

FIGS. 3A and 3B are graphs showing the discharging states in the cases of using various spacer materials, respectively;

FIG. 4 is a cross-sectional view of the principal part of a discharge display device, for explaining it; and

DESCRIPTION OF THE PREFERRED EMBODIMENT

With reference to the drawings, an embodiment of this invention will hereinafter be described.

FIG. 1A is a fragmentary perspective view showing, partly in cross-section, a discharge display device in accordance with one embodiment of this invention.

FIG. 1B is an exploded perspective view showing the principal part of the discharge display device exemplified in FIG. 1A.

In FIGS. 1A and 1B, reference numeral 1 indicates generally a discharge display device. The discharge display device 1 comprises upper and lower insulating plates 2 and 3 which are disposed in opposing relation to each other and at least one of which is formed of transparent material such, for example, as glass, and insulative spacer 5 which has bored therethrough plurality of apertures 4 in a matrix manner (referring to FIG. 1B) and is disposed between the upper and lower insulating plates 2 and 3. Between the upper and lower insulating plates 2 and 3, there is disposed an anode 7 which is transparent in this embodiment, an insulating spacer 5, there is disposed an anode 7 which is composed of a plurality of plate-shaped strip elements A₀, A₁, A₂, - - - and A_n. In this case, the elements A₀, A₁, A₂, - - - and A_n are disposed side in opposing relation to the columns of apertures 4 bored in the spacer 5 in a matrix manner. The lower plate 3 and the spacer 5, there is a cathode 8 which is composed of a plurality of shaped strip cathode elements K₀, K₁, - - - and K_n which are disposed side in opposing relation to the rows of apertures 4 bored in the spacer 5. Thus, the cathode elements K₀, K₁, - - - and K_n cross the anode elements A₀, A₁, A₂, - - - and A_n at right angles thereto, respectively.

After assembling of the above, said parts are sealed by means of an adhesive 10, or the like to provide an envelope 1a. The envelope 1a is evacuated through an exhaust pipe 1a. The inert gas such as neon, xenon, argon, like is sealed in the envelope 1a through the exhaust pipe 9b, thus providing the discharge pipe 9b, of the inert gas in the envelope 1a.

With such a construction, the application between selected ones of the cathode elements K₀ and A₀ - - - produces a discharge aperture 4 of the spacer 5 corresponding to the selected point of the selected cathode elements to emit glow light. Accordingly, in this case, the cathode elements K₀ and A₀ - - - formed therein apertures 8a are those 4 of the spacer 5 so that a

reservoir 9 is formed in the spacer 5 so that a

reservoir 9 is formed in the spacer 5 so that a

As illustrated in FIG. 2A, the spacer 5 is formed of a conductive metal plate 5a which is covered with an insulating layer 5b over the entire areas thereof including the peripheral surface of the aperture 4. The insulating layer 5b is formed porous to permit the passage therethrough of electrons and ions which are produced as upon discharge and this layer should not be formed as a dense layer such as glass or mica. The porous insulating layer 5b can be obtained by spraying a chromium oxide or alumina powder material onto both sides of the conductive metal plate 5a together with water glass and then baking the plate 5a. In this case, the temperature 5b is required to have a heat resistance temperature higher than 400°C and, further, since a local magnetic field sometimes exhibits a particular high intensity during discharging of the discharge display device, the insulating layer 5b is required to have a uniform withstand voltage higher than 250 V_{ac}. Therefore, it is 20 intended to check uniformity of the withstand voltage by measuring it, for example, the insulating layer 5b by measuring it, for example, a measuring instrument employing a brush electrical 15 manufacture of the discharge invention in which the invention is 3A, FIG. 3B is As the a

In FIGS. 3A and 3B, reference character P_1 indicates instants of turning on the switch P_2 indicates firing instants. The firing instants each correspond to the highest potential and, at this instant, the potential is lost due to discharging.

FIG. 3A indicates that, in the cathode element K_7 , there are some occasions when the firing instant P_2 is delayed as compared with the others and no discharge is produced. In FIG. 3B, however, the cathode elements are discharged at substantially equal time intervals and, at this time, the potential of the spacer 5 is $35 V_{dc}$ and no delay appears.

will hereinafter be further described. The effect of the envelope 1a. The effect of the discharge tube. FIG. 4 is a fragmentary cross-sectional view showing the relationship between the anode 7 and the cathode 8 of a discharge tube. FIG. 5 is a cross-sectional view of the spacer 5 in which the spacer 5 is formed of a glass material g. FIG. 6 is a cross-sectional view of the spacer 5 in which the metal plate 5a and the metal conductor, that is, the metal plate 5a and the metal plate 5a is adapted to be supplied with a voltage from a battery B through a resistor R₁ and a switch S. FIG. 7 is a cross-sectional view of the spacer 5 in which the insulating layer 5c on the metal plate 5a in FIG. 6 is removed. FIG. 8 is a cross-sectional view of the spacer 5 in which the insulating porous layer 5b. figures illustrate the acting conditions of electrons and neon ions Ne⁺ during discharge. Reference 11 identifies a plasma space in the discharge plasma space 11, during discharge.

In the plasma space 11, during discharge, charged particles are diffused and recombined with one another to be extinguished. The charged particles do not so much have an affect on the other cathode elements spaced away from the cathode element being discharged. Since the ions are especially large in size compared with the electrons, they tend to not affect the cathode elements.

on the formation of a neighboring discharge as compared with the ions, as described previously.

anode 7 and the cathode 8 in the direction b is dependent upon a voltage e_z therebetween during discharge.

In fact, the magnitude of the voltage e_z is related to the discharge of the next cathode element, but the speed of the electrons in the direction a perpendicular to the direction b has a strong relation to the discharge of the next cathode element and the start of discharge of the next cathode element is rapid.

By the way, in the case of FIG. 5, the electrons e produced by discharge readily adhere to the exposed glass surface as shown and attract ions to extinguish them, thus decreasing electrons promoting discharging of the next cathode element in the plasma space 11.

In the case of FIG. 6, neon ions are attracted to adhere to the surface of the insulating layer 5c and they are combined with electrons to provide the same results as shown in FIG. 5. Even if a voltage is applied to the metal plate 5a from the battery B, the same results are obtained.

Further, in the case of FIG. 7, when no voltage is applied, electrons decrease as in the case with FIG. 5. Upon application of a voltage, electrons e jump into a free electron layer on the conductor 5a more rapidly and ions are combined with free electrons, so that the same results are obtained.

In this case, by lowering the potential of the conductor 5a to the ground potential, electrons e are prevented from jumping into the conductor 5a, and consequently the amount of electrons e in the space 11 is increased, whereby the response time can be decreased. This results in a discharge between the anode 7 and the spacer 5, which implies that the spacer 5 serves as a cathode.

In FIG. 8 employing the spacer 5 of the present invention, the following assumption is probable. Namely, during discharging, electrons e generated in the plasma space 11 enter into the porous insulating layer 5b to lower its potential as compared with the conductor 5a. As a result of this, due to the intensity difference of the electric fields, the electrons go into the conductor 5a and propagate therein and, at the next discharging electrode position, they go out of the conductor 5a due to the electric field established between the anode 7 and the conductor 5a. However, these electrons of insufficient energy remain in the insulating layer 5b or on its surface and prevent movement of other electrons which are to enter into the conductor 5a from the plasma space 11 through the insulating layer 5b, or repel and direct them in the direction a , thus facilitating discharge of the next cathode element.

The following table shows the experimental values obtained with the spacers described above.

spacing between adjacent ones of the cathode elements is large, the response time interval is short and the discharge is carried out positively.

The discharge conditions shown in FIG. 3B can be understood from the above and the response time interval can be shortened. Accordingly, the discharge display device of this invention can be employed as a plasma display in place of a Braun tube as mentioned previously and the spacer which is used for graphic display and TV picture display can be produced at lower cost and with more accuracy than those formed of glass.

Although the present invention has been described in connection with a spacer interposed between the anode and the cathode in discharge display, the invention is not limited specifically thereto. A part such, for example, as the inside of the envelope, which is exposed to the plasma space produced by discharge or which is exposed to positive and negative charges, is formed with the material according to this invention so that a conductor is deposited with a porous insulating layer. As a result, the inside surface of the envelope thus formed shifts discharges rapidly.

With the present invention described above, the priming electrodes and isotopes used in the prior art become unnecessary.

It will be apparent that many modifications and variations may be effected by one skilled in the art without departing from the scope of the novel concepts of this invention.

I claim as my invention:

1. A discharge display device comprising:
  - a. upper and lower plates of which at least one is transparent;
  - b. an adhesive material sealing said upper and lower plates in an air-tight manner along their outer edges to form an envelope;
  - c. a spacer disposed between said upper and lower plates;
  - d. a plurality of cathodes disposed between said lower plate and said spacer;
  - e. at least one anode disposed in opposed relation to said plurality of cathodes and mounted between said upper plate and said spacer; and
  - f. an inert gas sealed within said envelope; and said spacer formed of a conductive plate covered with an insulating layer of porous material.

2. A discharge display device comprising:

- a. upper and lower plates of which at least one is transparent;

Table

No	Materials of trial manufacture(spacer)	Measured Results	
		Distance between K ₁ & K ₂ (mm)	Delay of discharge time interval (t ₂) of K ₂ (μsec.)
1	Insulating material (the case of FIG. 5)	2.54 7.5	30-100 longer than 100
2	Dense insulating material deposited on conductor (the case of FIG. 6)	2.54 7.5	30-100 longer than 100
3B	Conductor (the case of FIG. 7, +100V applied to conductor through resistor of 300KΩ)	2.54 2.54 2.54	30-100 longer than 100 80 longer than 100
4	Metal spacer of this invention (the case of FIG. 8, +160V applied to metal plate through resistor of 300KΩ)	100 100 7.5	20 40 longer than 100

As is apparent from the above table, too, when the spacer of the present invention is used, even if the

- b. an adhesive material sealing said upper and lower plates in an air-tight manner along their outer edges to form an envelope;
  - c. a spacer disposed between said upper and lower plates;
  - d. a plurality of strip cathodes disposed side by side between said spacer and said lower plate and selectively supplied with a voltage;
  - e. a plurality of strip anodes disposed side by side between said spacer and said upper plate and extending at right angles to said plurality of cathodes;
  - f. an inert gas sealed within said envelope, and said spacer formed of a plate of conductive material covered with a layer of porous insulating material.
3. A discharge display device as claimed in claim 2, in which said spacer consists of a metal plate and a porous

insulating layer formed on the surface of said metal plate.

4. A discharge display device as claimed in claim 3, in which said porous insulating layer contains chromium oxide powders.

5. A discharge display device as claimed in claim 3, in which said porous insulating layer contains alumina powders.

10 6. A discharge display device as claimed in claim 2, in which said lower plate is covered with an insulating porous layer on its inside surface.

15 7. A discharge display device as claimed in claim 6, in which the peripheral portion of said upper plate is covered with an insulating porous layer.
